TIME FUSE

Stanley Farrow, Denville, N. J., assignor to the
Government of the United States of America,
represented by the Secretary of War

Application April 4, 1938, Serial No. 199,859

4 Claims. (Cl. 102—82)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a time fuse.

The purpose of the invention is to provide an inexpensive and easily assembled time fuse in which ignition may be instituted inside of a container, unaffected by temperature, humidity and barometric pressure or by velocity and rotation of the projectile.

This is accomplished by placing a catalyst and a gaseous reactant in separate chambers, arranging for release of the gaseous reactant and providing for timed regulation of the passage of the gas into contact with the catalyst in sufficient concentration to heat it and produce ignition.

To these and other ends, the invention consists in the construction, arrangement and combination of elements described hereinafter and pointed out in the claims forming a part of this specification.

A practical embodiment of the invention is illustrated in the accompanying drawing, wherein:

Fig. 1 is a longitudinal sectional view, partly in elevation, of a fuse constructed in accordance with the invention;

Fig. 2 is a plan view of the movable disk;

Fig. 3 is a plan view of the fixed disk;

Fig. 4 is a longitudinal sectional view showing the application of the invention to an impact fuse;

Fig. 5 is an enlarged sectional view of the head of the fuse of Fig. 4;

Fig. 6 is a sectional view of a unit in which a low pressure gas is used.

Referring to Figs. 1 to 3 there is shown a fuse casing comprising a body 5 having a counterbored recess to provide an inner chamber 6 and to receive in its outer portion a head 7 which has a chamber 8 in its inner end. The head is arranged for rotation with respect to the body and to this end it is formed with an annular groove 9 which receives the inner ends of pins 10—10 carried by the body.

The body 5 carries a catalyst 11 such as platinum sponge, one portion of which is exposed in the chamber 6 and another portion of which is in contact with or in the vicinity of an ignition charge or an initiator 12 for detonating a booster charge 13.

The head 7 is provided with a chamber 14 terminating short of the chamber 8 and having its

mouth closed by a plug 15. A closed container 16 held in the rear end of the chamber 14 in any convenient manner is filled with a gas, such as hydrogen, which is capable of causing the catalyst 11 to become heated and produce ignition of the gas or the charge 12. The means for breaking the container to release the gas consists of a plunger 17 having a point 18 and the gas when released flows to the chamber 8 through passages 19 formed in the head 7. The plunger is normally held in the mouth of the chamber 14 by means of a resilient split ring 20 which is partially disposed within a groove 21 in the plunger and engages the lip 22 of the chamber. When a projectile equipped with the fuse is fired from a gun, the force of set-back causes the plunger to be driven rearwardly out of the grasp of the split ring 20 and puncture the container.

A pair of disks 23 and 24 constituting a valve, are interposed between the chambers 6 and 8 and are attached respectively to the body 5 and head 7 by screws 25 and 26. The disk 23 is provided in one-half of its surface with a plurality of small apertures 27, while the disk 24 is provided with a single semi-circular opening 28. When the disks are arranged so that the solid portion of the disk 24 overlies the apertured portion of the disk 23 communication between the chambers 6 and 8 is interrupted. By rotating the head 7 and with it the disk 24, the number of apertures 27 establishing communication between the chambers 8 and 6 may be regulated. This adjustment determines the rate of flow of gas from the chamber 8 to the chamber 6 and may be interpreted in units of time which are indicated externally of the fuse by means of a time scale 29 which is inscribed on the head and read against an index 30 on the body.

In the above illustration, the gas in the container 16 is under high pressure with a relatively large pressure difference existing between the chambers 6 and 8. The rate of flow through the apertures 27 will be dependent of the ratio of pressures and will be constant according to the law of the flow of gases.

In the fuse shown in Figs. 4 and 5 the positions of the gas container 31 and the plunger 32 are reversed and are respectively held against rearward movement on set-back by a split ring 33 and by means of a shoulder 34 formed in the fuse head 35. The plunger is normally held against forward movement by a resilient split ring 36. On impact of the fuse the plunger moves forwardly due to inertia and punctures the con-

tainer 31. The period of delay before heating of the catalyst 31 to produce ignition may be controlled by a valve mechanism as in Fig. 1 or by regulating the flow of the gas through appropriately dimensioned passages 38 in the plunger.

In the more or less schematic illustration of Fig. 6 the container 39 is filled with a gas under low pressure. The chamber 40 in which the container 39 is placed is of such size that the pressure of the gas upon being released drops to about one-half of its original pressure. A membrane or diaphragm 41 separating the chamber 40 from the chamber 42 containing the catalyst 43 is made of a porous material such as fabric. With the rate of diffusion of the gas through the diaphragm being known the time required for the gas to be present in chamber 42 in sufficient concentration to react on the catalyst may be readily determined. If a vacuum is created in chamber 42, the passage of the gas into it will be hastened. The container is arranged to be punctured on set-back of a plunger 44.

I claim:

1. In a fuse, a base, a catalyst in the base, a head rotatably carried by the base, a container in the head carrying a gas under pressure and capable of reacting with the catalyst to cause it to heat and produce ignition, means for opening the container at a predetermined time, and valved means between the catalyst and container constructed and arranged for varying the rate of flow of gas into contact with the catalyst whereby the time required to produce ignition after said container is opened may be varied.

2. A fuse having chambers, a catalyst in one 35

chamber, a container in the other chamber carrying a gas under pressure and capable of reacting with the catalyst to cause it to heat and produce ignition, inertial means for opening the container in response to acceleration of said fuse and means constructed and arranged for varying the rate of flow of gas into the chamber containing the catalyst whereby the time required to produce ignition after said container is opened may be varied.

3. In a fuse, a catalyst, a container carrying a gas under pressure and capable of reacting with the catalyst to heat it and produce ignition, means for opening the container at a predetermined time and means constructed and arranged for varying the rate of flow of gas into contact with the catalyst whereby the time required to produce ignition after said container is opened may be varied.

15.

20 4. In combination, a shell, a fuse comprising, a chamber, a finely divided catalyst in said chamber, a sealed container carrying a gas under pressure and capable of reacting with said catalyst to cause it to heat and produce ignition, inertial means for puncturing said container in response to acceleration of said shell, valve means interposed between said chamber and said container constructed and arranged for pre-determining the rate of flow of said gas into said chamber and into contact with said catalyst whereby the time required to produce ignition, after the said container is punctured, may be varied.

STANLEY FARROW.
